DUMP TRUCK

Jacob W. Ahola, Decatur, Bernard E. Erlacher, Washington, and Richard E. Guhl, Samuel L. Kershaw, and Alfred W. Sieving, Decatur, Ill., assignors to Caterpillar Tractor Co., Peoria, Ill.

Filed Jan. 30, 1974, Ser. No. 437,988

Term of patent 14 years

Int. Cl. D12—08

U.S. Cl. D12—15

FIG-1-

FIG-2-

FIG-3-

FIG-4-

FIG. 5

FIG. 6

FIG. 1 is a side elevational view of a dump truck embodying our new design.

FIG. 2 is a side elevational view thereof opposite to the side shown in FIG. 1.

FIG. 3 is a front elevational view thereof.

FIG. 4 is a rear elevational view thereof.

FIG. 5 is a top plan view thereof.

FIG. 6 is a bottom plan view thereof.

We claim:

The ornamental design for a dump truck, substantially as shown.
